LINEAR ACCELERATOR FOR CANCER RADIOTHERAPY OR THE LIKE

Jacob Haimson and Ronald E. Haynes, both of Palo Alto,
Calif., assignors to Varian Associates, Palo Alto, Calif.,
a corporation of California

Filed Aug. 21, 1961, Ser. No. 66,445

Term of patent 14 years

(Cl. D83—1)

FIG. 1

FIG. 2

FIG. 3

FIG. 4

FIG. 1 is a side elevational view of a linear accelerator for cancer radiotherapy or the like showing our new design, the opposite side being substantially a mirror image;

FIG. 2 is a plan view thereof; and

FIG. 3 is a front elevational view thereof.

FIG. 4 is an enlarged front perspective view thereof. The rear is substantially plain.

We claim:

The ornamental design for a linear accelerator for cancer radiotherapy or the like, as shown and described.
